UNITED STATES PATENT OFFICE.

JOHN D. KARLE, OF ROSELLE PARK, NEW JERSEY.

SAFETY LATHE DOG.

Application filed July 3, 1924. Serial No. 723,983.

This invention relates to improvements in work-gripping dogs more particularly of the type commonly called lathe-dogs designed to grip the work to cause rotation thereof during a machining operation thereupon.

The primary object of the present invention is to provide an improved safety lathe-dog which has no dangerous work-securing elements such as set-screws and the like projecting therefrom and which will permit of insertion and removal of a fair range or sizes of work with greater facility and rapidity than was heretofore possible.

A further aim of this invention is to provide a safety-dog capable of securely gripping circular as well as slab-sided work, wherein the work-gripping action is augmented in use by the machine operation upon the work regardless of the direction of rotation thereof.

Other objects of the invention will be apparent from the following description and claims.

In its preferred embodiment the present improved lathe-dog comprises a body from which projects the usual driving-tail and which body is provided with a work-receiving aperture defined by converging side-walls. Positioned upon the lathe-dog body to project within the work-receiving aperture is a circular friction-cam which is journaled for rotation upon an axis disposed eccentric to the peripheral surface of the friction-cam. This friction-cam is journaled upon a slide-block adjustably secured upon the lathe-dog body to permit of ready manual manipulation to alter the gripping position of the cam for various sizes of work. The converging side-walls of the work-receiving aperture, together with the friction-cam peripheral surface, afford in effect a three-point engagement with the work, relative rotation in either direction of the work and the gripping surfaces effecting a secure gripping of the work. This construction not only greatly facilitates insertion and removal of the work and thereby speeds production, but also conforms strictly to the modern requirements in eliminating dangerous work-securing projections such as set-screws and the like.

In the accompanying drawings, Fig. 1 is a perspective view of one form of the present improved lathe-dog, with the parts shown in detached relationship. Fig. 2 is a longitu-

dinal sectional view of the lathe-dog illustrating its work-gripping action, and Fig. 3 is a side elevation of the improved lathe-dog.

Referring to the drawings, the present construction comprises the stock or body 1 from which projects a common form of driving-tail 2, although other forms of driving-tails may obviously be employed. The body 1 is provided with a work-receiving aperture 3 having converging side-walls 4 comprising work-gripping surfaces against which the work 5 is forced by a rotary circular friction-cam 6 disposed opposite to the apex 7 of the aperture. The friction-cam 6 is so disposed upon the jaw that in its operative position its knurled peripheral-surface 8 projects within the aperture 3, said peripheral-surface 8 being eccentric to the axis of rotation of the friction-cam.

The friction-cam 6 is shown as journaled upon a pin 9 disposed upon a slide-block 10 to intersect a cam-receiving slot 11 provided in said slide-block. The slide-block 10 is slidingly fitted within a rectangular guide-way 12 provided in the body 1 and is confined to oppositely directed movements therein by a cover-plate 13 secured upon the body 1 by screws, as 14. The slide-block 10 is provided with a threaded aperture 15 entered by an adjusting screw 16, the knurled head 17 of which is provided with a plurality of peripheral apertures 18 and projects through a transverse slot 19 provided in the body 1, thereby holding the screw 16 against endwise movement when rotated and consequently effecting adjustment of the slide-block. To provide for more ready access to the screw-head 17 without unduly enlarging the same, the body 1 adjacent the head 17 may be beveled as at 20, this construction keeping the screw-head 17 from projecting any appreciable extent beyond the outer limits of the main-portion of the body 1. In order to limit the advancing movement of the slide-block 10 to prevent accidental detachment of the screw 16 therefrom, said slide-block is provided with a stop-pin 21 disposed in a slot 22 formed in the cover-plate 13, the limit of advancing movement being evidently determined by the inner end of the slot.

It will be apparent that when the slide-block 10 occupies a given adjusted position, the work such as is indicated at 5, may be inserted within the aperture 3 whereupon relative rotary movement between the work

and the lathe-dog will cause rotation of the friction-cam. This rotation of the cam will obviously effect a secure gripping of the work at three points, one of which lies 5 in the periphery of the cam and one in each of the converging surfaces 4. Should now a machining operation be attempted upon the work in a manner such that the operating tool has a tendency to rotate the work in 10 the same direction as that in which it was turned to grip it in the dog, the tool-action will merely augment the gripping action of the friction-cam upon the work, whereby the work is firmly held against slippage. 15 Nevertheless, after the machining operation is completed, a slight turning of the work in the opposite direction will immediately release it from the friction-cam.

Any given adjusted position of the friction-cam will evidently accommodate a moderate degree of variation in sizes of the work without further adjustment. The adaptability of the present improved lathe-dog to 20 different sizes of work is particularly advantageous owing to the saving of time obtained, all that is necessary being the insertion of the work within the dog and the action of the machine-tool will itself cause the work to be instantly and securely gripped 25 regardless of the direction of rotation of the work.

When the range in work-sizes is greater than can be accommodated by the eccentricity of the friction-cam in a given adjusted 30 position, it is only necessary to reposition the same by manipulating the head 17 of the screw 16. For certain classes of work, such as cutting screw-threads, the tool action upon the work is successively in reverse 35 directions and the reversal of the direction of action of the tool would tend to release the work from the dog and then immediately cause a regripping thereof. This slight period of non-rotation of the work may be 40 undesirable for certain operations and when work of this character is positioned in the aperture 3, a suitable tool may be inserted 45 in any one of the peripheral apertures 18 in the screw-head 17 and the screw further rotated whereby the work is so firmly gripped by the consequent jamming action 50 that loosening of the work under the reverse

action of the tool is impossible. This same means may be employed for releasing any jammed work. 55

Having thus set forth the nature of the invention, what I claim herein is—

1. A safety lathe-dog including a body having a work-receiving aperture, an eccentrically-journalized peripherally-circular friction-cam disposed upon said body for complete rotation in opposite directions and projecting within said aperture to grip work by relative rotation between the work and lathe-dog in either of two opposite directions, and manually adjustable means for shifting the axis of rotation of said cam to predetermine its degree of projection within said aperture. 60

2. A safety lathe-dog including a body 70 having a work-receiving aperture, a rotary friction-cam disposed upon said body for complete rotation in opposite directions projecting within said aperture, and manually adjustable means for determining the degree 75 of projection within said aperture of the friction-cam to accommodate different sizes of work.

3. A safety lathe-dog including a body having a work-receiving aperture, a rotary 80 friction-cam disposed upon said body to project within said aperture, an adjusting screw held against endwise movement on said body for determining the degree of projection within said aperture of the friction-cam, 85 and a stop for limiting the degree of adjustment effected by manipulation of said screw.

4. A safety lathe-dog comprising a body free of projecting set-screws having a work-receiving aperture defined by convergent 90 work-engaging surfaces, a friction-cam opposed to said surfaces, a slide-block rotatively sustaining said friction-cam, a guideway in said body for the slide-block, and an adjusting-screw threaded into said slide-block 95 for determining the position of the friction-cam with respect to said surfaces, said adjusting screw having its manipulating head disposed within a transverse slot provided in the lathe-dog body whereby the screw is 100 held against endwise movement.

In testimony whereof I affix my signature.

JOHN D. KARLE.
